UNITED STATES PATENT OFFICE

SIGMUND GESTETNER, OF TOTTENHAM HALE, LONDON, ENGLAND, ASSIGNOR, BY
MESNE ASSIGNMENTS, TO A. B. DICK COMPANY, OF CHICAGO, ILLINOIS, A CORPO-
RATION OF ILLINOIS

DUPLICATING WITH THE AID OF STENCILS

Application filed March 30, 1931. Serial No. 526,462.

This invention relates to rotary stencil duplicating machines of the kind with which a relatively viscous or pasty ink is employed and in which the ink is distributed over the 5 surfaces of a plurality of non-porous inking cylinders by which it is forced through the openings in the stencil, the latter being normally mounted on a flexible stencil carrier secured to endless bands in driving engagement with the cylinders by the rotation of 10 which the stencil is caused to travel over the surface of the inking cylinders, the impression-receiving material being fed between one of these cylinders and a pressure 15 roller.

Hitherto, with such machines, one end of the stencil, commonly described as the stencil heading, is engaged by fastening means provided on a member extending between 20 the flexible bands in contact with a silk sheet, one end of which is also engaged with the member in question, the other end of the silk sheet being connected with a substantially rigid element extending from one band to 25 the other band and being connected, in turn, with a member also extending across the machine and spaced apart from the first-mentioned member in order to permit ink to be applied to the surface of the cylinders, the 30 second mentioned member being connected by a piece of flexible ink-impermeable material with the member on which the fastening means for the stencil is provided.

With this arrangement, hitherto it has 35 been possible, in the event of the ink being or becoming relatively fluid, particularly with high speeds of operation of the machine, for ink to be thrown off the cylinders.

The object of the present invention is to 40 provide means for preventing such a possibility.

According to the invention, with the substantially rigid element connected with the end of the silk sheet remote from the stencil 45 fastening means is hingedly connected a hinged flap adapted to extend from the member in question and to bridge over the opening enabling ink to be supplied to the inking cylinders.

50 Preferably, in accordance with the inven-

tion with the flap is associated springs adapted to constrain the flap to move into the position in which it bridges or covers the opening and the springs in question are, preferably, so arranged that on moving the flap about its hinged connection, in order to permit ink to be delivered on to the cylinders, it will be moved over its dead centre and retained in the open position by the spring.

55 Thus, in accordance with the invention, 60 projections may be provided on the flap, each of such projections engaging one end of a spring, the opposite end of which is connected with the rigid member extending across the machine and forming an abutment for the free edge of the flap.

65 The connection between the ends of the flaps remote from their connection with the flap may each comprise a stirrup element 70 adapted to engage a projection on one end of the rigid member in question, the projection being constituted by the end of a bolt whereby the said element is secured in known manner to the flexible bands.

75 One construction in accordance with the invention will be illustrated by way of example with reference to the accompanying drawings, in which:—

Figure 1 is a view partly in section of a 80 duplicating machine of generally known type and provided with a device in accordance with the invention;

Figure 2 is a view in perspective illustrating the application of the device to the inking cylinders of such a machine;

Figure 3 is a front view in elevation of the 85 machine with the device in the position adapted to permit ink to be applied to the upper inking cylinder;

Figure 4 is a view of the device associated 90 with a silk sheet, and

Figure 5 is an end elevation on an enlarged scale of the flap and its associated parts.

The duplicating machine illustrated is generally of the character described in the 95 United States specification No. 700,031 and in Figures 1, 2 and 3 of the drawings, 1 and 1a represent, respectively, the upper and lower inking cylinders. These cylinders are provided with spindles 2 and 2a which, as 100

shown in Figures 1 and 2, are engaged in bearings in the side members 3 which are secured to a base plate 4 and form therewith the main frame of the machine.

5 By means of the handle 5 on the spindle 6 on which is mounted the pinion 7, meshing with the spur wheel 8 mounted upon the spindle 2a of the inking cylinder 1a, the said inking cylinder may be rotated and in consequence of the engagement of the pins 9 in holes provided in the flexible members 10, corresponding motion is imparted to the inking cylinder 1.

15 With the inking cylinders are arranged to cooperate, in the normal operation of the machine, a pair of waver rollers 11, the spindles 12 of which are engaged in slots 13 in the blocks 14 which are slidably mounted in slots in the ends of the pivoted lever 15 the blocks 20 being connected together by a spring 16 adapted to force the waver rollers into contact with the inking cylinder.

25 This lever is mounted upon a pivot 15a and in an arm of this lever there is engaged one arm of the lever 17 which is adapted to be oscillated about the spindle 2a and by its oscillation it imparts to the lever 15 corresponding motion whereby the waver rollers are moved axially in order to assist in the distribution of the ink on the surface of the cylinders 1 and 1a. The other arm of the lever 17 is provided with a roller 18 mounted on a pin 19 and engaging the slot 20 in the link 21 which engages an eccentric 22 on the spur wheel 23 and is connected at the other end with a pin joint 24 with the lever 25 pivotally mounted on the pin 26 and oscillated about the said pin by the motion of the eccentric about the axis of rotation of the wheel 23 when the latter is rotated by rotation of the spur wheel 8.

30 The lever 25 is pivotally connected by the pin 27 with the wedge shaped member 28 and by the oscillation of the lever 25 the wedge-shaped member is reciprocated. This motion of the wedge-shaped member between the roller 29 mounted upon the pin 30 and the roller 31 on the link 32 which is provided with slots 33 and 34 engaging, respectively, 35 the spindle 35 on which the wheel 23 is mounted and the pin 30, causes the link to lift from the position shown in Figure 1 and in lifting it carries with it a plate 36 secured by the pin 37 to the link 32 thereby causing the hooked shaped portion 38 of the plate to engage the pin 39 on the arm 40 which is connected to a similar arm on the opposite side of the machine by the bar 41 pivotally mounted in the side members of the frame of the machine and 40 thus to move the arm in an upward direction about the axis of the bar thereby raising the collars 42 with which they are pivotally connected by screws 43.

45 These collars are slidably mounted upon the rods 44 forming an extension of the side

members 45 of the carriage in which the pressure roller 46 is mounted and between the collars and the upper portion of the side members of the carriage, which are pivotally connected by the pins 47 with the arms 48 pivotally mounted on the pins 49 on the side frame of the machine, there are arranged springs 50 so that in the raising of the collars the pressure roller will be caused to be resiliently pressed, in the normal operation of the machine, on the sheet of paper or other impression-receiving material to be operated upon by the stencil.

50 The member 51 extends between the flexible bands and is provided with fastening means 52 adapted to engage a stencil heading, the body of the stencil being arranged in contact with a silk sheet 53 one end of which is also engaged with the member 54 the other end of the silk sheet being connected with a substantially rigid element 55 extending from the band on one side of the machine to a similar band on the other side. To this rigid element which is not directly connected with these bands is connected a flap 56 by a hinge pin 57 engaging in a turned over edge 58 of the flap 56 and in lugs 59 on the rigid element.

55 On the flap 56 there are provided two projections 60 and 60a with the former of which one end of a spring 61 and with the other, one end of a spring 61a is connected, the other ends of the spring being provided with a stirrup element 62, 62a which are engaged (see particularly Figures 2 and 3) with the 60 projections 63, 63a on the opposite ends of a rigid member 64 in turn connected by a piece of flexible material 65 with the member provided with the fastening means for the stencil heading.

60 In the normal operation of the machine, the flap 56 will be in the position shown in Figure 2 and the flange 66 thereon will cooperate with the adjacent edge of the rigid member 64. When occasion arises to re-ink the machine the flap may be moved about its hinge into the position shown in Figures 1 and 3 thus exposing a portion of the upper inking cylinder 1a to the surface of which ink is applied. Thereafter the flap is moved into the position shown in Figure 2, being retained in this position by the tension of the springs and remaining in this position during the operation of forming stencil impressions, the springs also operating to draw the substantially rigid element 55 connected with one end of the silk sheet 53, forward or towards the member 64 thus maintaining the silk sheet taut.

65 What I claim is:—

1. A stencil carrier for rotary duplicating machines of the kind with which a relatively viscous or pasty ink is employed comprising a sheet of flexible foraminous material in contact with which the stencil is

- secured, a rigid member connected to one end of said sheet and a hinged flap connected with the rigid member and springs associated with the flap.
- 5 2. A stencil carrier for rotary duplicating machines of the kind with which a relatively viscous or pasty ink is employed comprising a sheet of flexible foraminous material in contact with which the stencil is secured, a
- 10 rigid member connected to one end of said sheet and a hinged flap connected with the rigid member, a lug on one side of the rigid member, a lug on the opposite side thereof, one end of a spring connected with one lug,
- 15 a stirrup on the opposite end of said spring, one end of a spring connected with the second lug and a stirrup on the other end of said spring.
3. A stencil carrier for rotary duplicating
- 20 machines having a flexible foraminous stencil carrier, a rigid member connected to each end of said stencil carrier, a hinged flap mounted to close the space between the ends of said stencil carrier and springs associated with
- 25 the flap to maintain said flap closed and said carrier taut.
4. The combination with a rotary stencil duplicating machine having inking cylinders, and a flexible stencil carrier mounted to
- 30 travel around said cylinders and having a rigid member connected to each end thereof, of means for closing the space between the ends of said carrier comprising a flap hinged at one edge to one of said rigid members and
- 35 adapted to bear at its opposite edge on the other rigid member, and spring means connected between the flap and one of said rigid members adapted to yieldingly retain said flap in closed position.
- 40 5. The combination with a rotary stencil duplicating machine having inking cylinders, and a flexible stencil carrier mounted to travel around said cylinders and having a rigid member connected to each end thereof, of
- 45 means for closing the space between the ends of said carrier comprising a flap hinged at one edge to one of said rigid members and adapted to bear at its opposite edge on the other rigid member, lugs on opposite sides
- 50 of said flap, and springs arranged between said lugs and the second mentioned rigid member to maintain the stencil carrier taut and the flap closed.
6. The combination with a rotary stencil
- 55 duplicating machine having inking cylinders, and a flexible stencil carrier mounted to travel around said cylinders and having a rigid member connected to each end thereof, of means for closing the space between the ends of said carrier comprising a flap hinged at one edge to one of said rigid members and adapted to bear at its opposite edge on the other rigid member, and springs connected
- 60 between the edges of the flap and the second mentioned rigid member and adapted to pass
- the axis of the flap hinge whereby said flap may be urged shut in one position of said springs and urged open in another position thereof.
- In testimony whereof I have signed my
- 70 name to this specification.
